UNITED STATES PATENT OFFICE.

GEORGE F. RAMM, OF DEL MONTE, CALIFORNIA.

RACK.

1,345,954.

Specification of Letters Patent.

Patented July 6, 1920.

Application filed October 29, 1917. Serial No. 198,915.

To all whom it may concern:

Be it known that I, GEORGE F. RAMM, a citizen of the United States, residing at Del Monte, in the county of Monterey and State of California, have invented new and useful Improvements in Racks, of which the following is a specification.

This invention relates to improvements in racks of the type used by laundries to hold 10 the piles of laundried wearing apparel of its patrons before the apparel is wrapped for delivery.

The racks for this purpose are of the portable type and have an open top and front. 15 The racks are approximately 9 feet long and 7 feet high and contain four or more shelves upon which articles of wearing apparel belonging to the various patrons of the laundry are placed by the assorter in piles after 20 the laundrying of these articles has been completed.

It is now the practice for the assorter when placing a laundried article upon the shelves of the rack to copy with chalk upon the 25 front of the shelf the identifying character with which the article is marked, so that the articles bearing the same identifying characters may be collected in one pile for the wrapping and delivering thereof, or to 30 place upon the article, or shelf a card or tag containing such characters.

I find from experience that where cards and tags are placed upon the articles or shelves they require frequent handling 35 which not only requires considerable time but permits the cards or tags to become mixed and often times hidden from view, so that the patrons of the laundry frequently receive articles of wearing apparel which 40 do not belong to them, thus causing annoyance to the patrons of the laundries and its employees.

When the identifying characters are marked on the front of the shelf with chalk 45 it is necessary for the assorter to reach upwardly a considerable distance when writing the designating characters upon the shelves adjacent the top of the rack, and when writing upon the shelves adjacent the 50 bottom of the rack, the assorter must stoop, or squat upon the floor. In either instance the assorter is in an uncomfortable position which usually results in the identifying characters being marked upon the 55 shelves in a careless, or incorrect manner.

To overcome this annoying feature inci-

dent to the sorting of laundried wearing apparel I provide a rack having detachably connected with the front thereof in line with the shelves a plurality of blackened strips 60 upon which the identifying characters may be marked.

Another object of the invention is to so construct hooks and plates and arrange the same upon the rack and strips that a strip 65 may be supported upon the rack in a convenient position for writing the indicating characters thereon, and afterward readily connected with the rack below any shelf desired.

With these and other objects in view, the invention resides in the novel combination and arrangement of parts, which will be hereinafter described and particularly pointed out in the claim.

The preferred embodiment of the invention has been illustrated in the accompanying drawings, although no restriction is necessarily made to the precise details of construction therein shown, as changes, alterations, and modifications within the scope 80 of the claim may be resorted to when desired.

In the drawings:—

Fig. 1 is a perspective view of a laundry rack constructed in accordance with the invention.

Fig. 2 is a fragmentary horizontal section on the line 2—2 of Fig. 1.

Fig. 3 is a front elevation of one of the 90 strips.

Fig. 4 is a perspective view of the plates with which the blackened strips are provided.

Fig. 5 is a detailed perspective view of 95 one of the hooks for supporting the strips.

Like characters of reference denote corresponding parts throughout the several views in the drawings.

Referring now to the drawings in detail 100 the letter A designates a laundry rack of the type now employed in laundries for holding the piles of assorted wearing apparel.

The rack A includes a base 5 from which 105 rise end walls 6 and a rear wall 7. The end and rear walls of the rack A serve to support a plurality of shelves 8 upon which the laundried articles are arranged in piles. Extending vertically of the rack A and arranged centrally of the front thereof is a 110 strip 9, to which and the front faces of the

ends are secured hooks 10. The hooks 10 which are arranged below the shelves 8 are formed from metallic strips 11 which are offset between their ends, as at 12 to space the bills 13 of the hooks from the shanks 14 which are connected with the rack A by securing elements 15. Supported upon the front of the rack A in line with the shelves 8 are strips 16 which are blackened, so that 10 identifying characters corresponding with the identifying characters upon the pile of wearing apparel upon the shelves may be marked upon the strips with chalk. Secured to the outer face of each strip 16 adjacent its ends are plates 17 upon one side edge of which is formed a flange 18 which extends outwardly from the outer face of the strips to contact with the bills of the hooks 10 at the ends of the shelf in line with 15 the strip, thereby locking the strip against movement longitudinally of the rack A.

To facilitate the positioning of the ends of the strips 16 behind the bills of the hooks on the ends of the rack A I provide each 20 strip 16 central of its outer face with another plate 19 at opposite sides of which I form flanges 20 for contact with the bills on the hooks on the strip 11.

When it is desired to connect one of the strips 16 with the rack A, for identifying the various piles of assorted laundry articles thereon, the assorter writes upon the front face of the strips with chalk identifying characters corresponding to those on the 25 piles of laundry articles. The assorter now stands in front of the strip 11 and holding the marked strips 16 in both hands places the bill of one of the hooks on the strip 11 between the flanges on the plate 19

on the strip, after which the strip 16 is lowered to rest upon the offset portion of the hooks adjacent the shelf with which the strip is aligned, the flanges on the plate 19 through their engagement with the bill on the hook on the central strip insures the 45 strip 16 remaining in a horizontal position, so that the plates 17 at the ends of the strips 16 will be received behind the bills of the hooks at the ends of the rack A.

The plates 19 not only serve to guide 50 the strips 16 into position upon the racks but also act as an auxiliary means for locking the strips against movement longitudinally of the rack.

From the foregoing description taken in 55 connection with the accompanying drawings it is apparent that a laundry rack has been provided embodying a simple and inexpensive indicating device which is highly efficient for the purpose intended.

Having thus described the invention, what is claimed as new, is:—

The combination with a rack comprising a vertical row of shelves, of hooks secured along the front of the rack and spaced from 65 the edge of the shelves, indicia bearing strips removably secured in said hooks and disposed along the front edge of the shelves to divide the latter into separate individually indicated spaces and flanged plates carried by the strips and engageable with the hooks to hold the strips against longitudinal movement.

In testimony whereof I affix my signature.
GEORGE F. RAMM.
